(57) **CLAIM**

The ornamental design for a pneumatic tool casing, as shown and described.

DESCRIPTION

FIG. 1 is a perspective view of a pneumatic tool casing showing my new design;

FIG. 2 is a top plan view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a bottom plan view thereof; and,

FIG. 8 is a perspective view thereof, wherein a pneumatic tool is engaged.

The broken lines shown in the drawings illustrate environmental structure and portions of the pneumatic tool casing that forms no part of claimed design.
